INVENTOR:

ELOI RODOLAUSSE

Elie Rodolause
ATTORNEY.

UNITED STATES PATENT OFFICE.

ELOI RODOLAUSSE, OF ST. ANTONIN, FRANCE.

SPEED-CONTROLLING DEVICE FOR RAILWAY AND TRAMWAY TRAINS.

Application filed December 2, 1922. Serial No. 604,591.

To all whom it may concern:

Be it known that I, ELOI RODOLAUSSE, a citizen of the French Republic, and resident of St. Antonin (Tarn and Garonne), France, have invented certain new and useful Improvements in Speed-Controlling Devices for Railway and Tramway Trains, of which the following is a specification.

This invention relates to improvements in or modifications of the invention set forth in the specifications of my U. S. Patent-applications No. 466432 filed May 3, 1921 and No. 563149 filed May 23, 1922.

In said specifications I have described a speed controlling device having a so-called speed supervising cam, held stationary as the train runs normally and released as the locomotive passes in front of a lug on the track prescribing a stopping or decrease of speed, said cam being thus moved through a complete revolution to actuate a member arranged so as to show the engineer the prescribed decrease of speed and cause the brakes to be applied and the train to be stopped should the speed not be decreased within the desired period of time.

Said cam is held in gear by the engagement of a lug made integral with the said cam with a stop lever, and thrown out of gear by the suitable swinging movement of said lever, caused either by the inflation of an air pocket or bag acting on said lever, or by an electro-magnet attracting said lever, the inflation of the air pocket and the throwing into circuit of the electro-magnet being effected automatically as the locomotive engages the lug on the track prescribing the stopping or decrease of speed.

One of my present improvements has for its object to combine with the device above mentioned an improved device for effecting the disengagement of the stop lever of the controlling cam by means of a lug on the track.

Said device comprises a cylinder, secured horizontally below the locomotive and connected by a conduit to the air pocket, the inflation of which throws the cam out of gear, said cylinder containing a spring actuated piston, the rod of which is connected to one end of a chain or other flexible operating member, stretched horizontally below the locomotive so as to engage the lug on the

track and, by the movement of the piston in its cylinder against the action of the piston spring, produce the suction of air into said cylinder and the forcing of such air into the air pocket by the expansion of the spring, as soon as the flexible operating member has moved beyond the lug on the track, the opposite end of said flexible member being attached to a rod which is also spring actuated and adapted to be moved lengthwise in a stationary bracket, so as to produce simultaneously—should a break occur in said flexible member—the closing of the circuit of the electro-magnet moving the stop lever of the controlling cam back to its disengaging position, and the opening of a valve, arranged on the main conduit of the brakes, for the purpose of obtaining an admission of compressed air into a second air-pocket and the disengagement of the controlling cam.

Thus as the train runs normally said new device permits of said cam being disengaged each time the flexible member engages the lug on the track, through the agency of the spring actuated piston connected to said member. Moreover should a damage or break occur in said chain, it enables the cam to be permanently disengaged by means of compressed air from the brake conduit being admitted in said second air pocket and by the closing of the circuit of the electro-magnet, both devices also functioning as the train runs normally, their action being combined with the action of the spring actuated piston.

A further object of my present invention is to provide a device which permits of speed controlling apparatus being applied to passenger trains all cars of which are provided with air brakes, as well as to goods trains having only a limited number of cars (four or five) having air brakes and running at a speed not exceeding 55 kilometers per hour for instance.

Said improvement consists primarily in the adjunction of a second controlling cam and a device designed to enable the engineer to bring the operating lever of the controlling pointer in front of either of said cams in order to thus obtain the lowering, towards the stopping position of the controlling pointer under such conditions that it pre-

scribes and causes the stopping of a train running at full speed or at low speed, according to the position given by the engineer from the outside of the cab to the operating lever of the controlling pointer in front of the one or the other cam.

10 A still further object of my present invention is to provide a device designed so as to limit the speed of the train according to the pressure of the compressed air of the brakes.

15 In the specifications referred to above I have described devices, producing automatically the application of brakes of the speed becomes excessive or if the engineer does not mind the stopping or decreases 20 of speed indicated by the so-called controlling pointer moving in front of the speed pointer, the rate of movement of which is a function of the speed of the train. With 25 said device limiting the speed to the pressure of the brake air, it may happen if the pressure in the main is low, that the train cannot be completely stopped within the prescribed distance of 1000 meters.

25 The novel device designed to avoid this objection by limiting the speed of the train to the pressure of compressed air of the brakes, is such that the normal stopping of a train is effective within the prescribed 30 distance of 1000 meters notwithstanding the pressure existing in the main conduit of the brakes.

It has also for its object to provide a second device designed to hasten or retard the 35 automatic application of the brakes according as the train runs down or up an incline.

Both devices act directly on the controlling pointer, the contact of which with the speed pointer causes the operation of the 40 auxiliary motive valve, and therefore the automatic application of the brakes as described in my prior patents.

In order to facilitate the comprehension of my invention, I have illustrated the new 45 devices by way of example in the accompanying drawings, wherein:

Fig. 1 represents the device for disengaging the stop lever of the controlling cam by a lug on the track.

50 Fig. 2 represents the second controlling cam and the device bringing the operating lever of the controlling pointer in front of the one or other cam according to the nature of the train.

55 Fig. 3 is a plan view corresponding to Fig. 2.

Fig. 4 is a diagram showing a sectional front elevation of the device for automatically advancing or retarding the moment of 60 the application of the brakes according to the inclination of the track, said device being represented in connection with certain parts for the supervising and controlling apparatus.

65 Fig. 5 is a fragmentary front elevation

of the device for limiting the speed according to the brake pressure.

Fig. 6 is a vertical section on line A—A of Fig. 5.

Fig. 7 is a fragmentary plan view of the 70 device shown in Figs. 5 and 6.

Referring more particularly to Fig. 1, the numerals 1, and 2 indicate two vertical arms forming a bracket which is rigidly secured in any suitable way below the locomotive. 75

The lower part of arm 1 carries a cylinder 3 adapted to swing in a horizontal plane in a double eye 4, rigidly secured to the end of said arm 1.

80 The interior of said cylinder is connected by means of a tube 5 of suitable cross section to an air-pocket 6 described in my aforesaid applications and serving to produce by its inflation the swinging movement 85 of the stop lever 7 of the supervising cam and the disengagement of said lever from the cam-stops 7'.

Arranged within said cylinder is a piston 8 adapted to be moved longitudinally and held, in normal running, in the position shown in the drawings by a coil-spring 9.

85 The rod 10 of said piston is provided at its free end with a double eye 11 to which is attached a chain 12 or other flexible member, such as wire-rope, serving to cause the longitudinal movements of the piston 8 within the cylinder 3 against the action of the spring 9, as will be explained herein-after.

90 Said chain or other flexible member is stretched horizontally below the locomotive, so as to be adapted to engage lugs on the track.

95 On the side of the arm 2 of the bracket, the chain 12 is attached to a double eye 13 secured to the end of a rod 14, which is suitably guided so as to slide in the inner bore 15 of a boss 16 made integral with the arm 2; said rod 14 having a shoulder 17, between which and the bottom of the bore 15 is inserted a spring 18, normally held under compression by the pull exerted on the flexible connection 12 by the stronger spring 9 of the piston 8.

100 The bore 15 is closed by means of screw-threaded plug 19, in which is suitably mounted a contact-finger 20, inserted into an electric circuit 20' serving to energize the electro-magnet 21, which moves the stop lever 7 to free the stop 7', as the rod 14 is moved back by the spring 18 and said circuit completed by the engagement of the shoulder 17 of the rod 14 and said finger 20.

105 Also guided in said plug 19 is the stem of a valve 22 arranged so as to normally cut off the communication between a conduit 23 branched on the main air conduit of the brakes and a conduit 24 communicating with a second air pocket 6^a, acting under 110

the same circumstances as the pocket 6 on the lever 7, said valve being opened as the rod 14 is forced back by the spring 18 in order to put the brake conduit into communication with the air pocket 6^a simultaneously with the closing of the circuit of the electro-magnet 21.

The mechanism so far described operates as follows: As the flexible member 12 engages a lug on the track prescribing a stopping or decrease of speed, said flexible member will be tensioned and causes the longitudinal movement of the piston 8 within the cylinder 3 against the action of the spring 9, said piston sucking a certain amount of air, which will then be suddenly forced into the air pocket 6, as soon as the flexible member 12 becomes disengaged from the lug on the track.

20 This forcing of air under the sudden expansion of the spring 9 results in the movement of the stop lever 7 from the stop 7' to free the cam.

During the expansion of the spring, the flexible member will be distended so that the rod 14 will be moved backwardly by the spring 18 to open the valve 22. This arrangement therefore, provides that the stop lever of the cam will be simultaneously subject to three different actions to bring the same to its disengaging position, whereby said disengagement will be secured in an absolutely reliable manner each time the flexible member engages a lug on the track prescribing a decrease of speed or stopping, and thus the speed controlling apparatus will be operated automatically at the desired precise moment.

The device for closing the circuit of the electro-magnet 21 as well as the device for opening the communication between the main conduit of the brakes and the second air pocket 6^a, will also be operated automatically through springs 9 and 15, if in normal running a break occurs in the flexible member 12, so that both devices constitute supplemental effective safety members, determining the operation of the controlling apparatus.

50 In Figs. 2 and 3, showing the device enabling the engineer to bring the operating lever of the supervising pointer either on the supervising cam described in my aforesaid applications or on the supplemental supervising cam, the supervising pointer 25 is carried by a pivot-pin 26 secured to a lever 27, adapted to turn around an axis 28 and which is to be moved by hand around the latter by the engineer by means of the index 29 in order to bring the supervising pointer 25—before the starting of the train—to the position corresponding to the maximum speed allowed to said train during its travel.

60 65 The index 29 arranged on the outside of

the apparatus will be moved to this end by hand in front of the segment 30 divided from 0 to 120, and is keyed on an axis 31 carrying a cam 32 which, acting directly on the lever 27 carrying the supervising pointer 25, therefore causes said pointer to swing and to stop in a position determined by the position of the index 29 on the scale 30.

As described in my aforesaid applications, the apparatus comprises a supervising cam 33 on which rests a lever 34 which swings freely around the axis 28 if said cam is automatically operated as described in my said applications, and engages by means of a stop screw 35 the lever 27 carrying the supervising pointer 25 and causes the latter to be lowered to the position indicating "stopping".

A second supervising cam 36 is keyed on the same shaft and is separated from the cam 33 by a disc 37.

The profile of both supervising cams is determined in such a way that the supervising pointer 25 if operated by either cam 33 or 36 and the lever 34, indicates to the engineer that it is necessary to decrease the speed of the train to bring the latter to a stopping within a determinate distance, the cam 33 being utilized for trains the maximum speed of which is comprised between 60 and 120 kilometers, whilst the cam 36 will be used for trains the maximum speed of which does not exceed 55 kilometers.

In order to permit of the lever 34 being brought in front of the supervising cam 33 corresponding to the maximum speed allowed, the shaft 31 carrying the index 29 on the outside of the apparatus, may be moved longitudinally by hand in its bearings and carries said lever 34 with it.

To this end said shaft 31 is provided with a finger 38 which may be brought into engagement with a projection 39 carried by the lever 34 and arranged so that its angular rotation determined by the index 29 in the direction of the arrow X raises the lever 34 above the disc 37 separating the two supervising cams 33 and 36, the finger 38 engaging a groove in the projection 39 and moreover locking together the shaft 31 and lever 34, thus transmitting to the latter the longitudinal movement imparted by hand to the index 29, thus arranging the lever 34 for co-operation with either cam at will.

In order to avoid any mistake by the engineer, the kilometric divisions on the stationary segment, over which the index 29 must be moved before the train starts, are arranged on two different planes, see Fig. 3, one of which bears the divisions from 60 to 120 kilometers, whilst the second plane bears the divisions from 55 to 0 kilometers. Moreover the shaft 31 will be held in either of its two end positions of longitudinal movement by the engagement in one of

the two notches 40 and 41 provided in a stationary stop member 42, of a disc 43, keyed on said shaft 31 and cut away at a suitable point of its periphery as shown at 5-44.

The result of this arrangement is that if the parts are in the positions shown in the drawings, the adjusting index 29 may be moved to any one of the divisions 60 to 120 10 on the scale of 30 and the lever 34 will be in contact with the supervising cam 33, which will thus actuate the supervising pointer 25, as previously described.

If the apparatus is to be used for controlling the speed and stoppings of a train running at a speed equal to or less than 55 15 kilometers per hour, the engineer, in order to bring the index 29 to the maximum speed allowed, must first raise said index in the direction of the arrow X until the notch 44 of the disc keyed on the shaft 31 will be brought in front of the stationary stop member 42.

This position of the index is determined 25 by the engagement of a tooth 45 of the disc 43 and said stop member.

During the raising of the index 29, the finger integral with shaft 31 engages the groove of the projection 39 carried by the 30 lever 34, so that the latter will be swung around the supporting axis 28 and brought above the rim of the disc 37 separating the two supervising cams 33 and 36, and then it will be sufficient to pull the index 29 towards the outside in order to bring the lever 34 above the second supervising cam 36.

Now the index 29 will be forward of the other plane formed on the scale 30 and may be moved by rotation in the direction of the 40 arrow X opposite the division corresponding to the maximum speed allowed, the disc 43 integral with shaft 31 being then engaged in the second notch 41 of the stop member 42.

If the index 29 moving in a direction of 45 the arrow X is raised to the dotted line position in Fig. 2, the disc 43 will be free of the notches of the stop 42 and longitudinal movement of the shaft 34 permitted to adjust the lever 34 for cooperation with the supervising cam 33.

From the foregoing it follows that the new device permits of the supervising lever being displaced from the outside of the 55 apparatus by simply moving the outer adjusting index, so that the adjusting will be simplified and may be effected without any mistake.

The device serving to advance or retard 60 the automatic application of the brakes, according as the train runs down or up an incline, and the device for limiting the speed according to the pressure in the brake conduits, are represented in Figs. 4 to 7 65 of the drawings.

The device limiting the speed of the train according to the pressure of compressed air in the main conduit is composed (see Fig. 5) of a cylinder 46 communicating with the main reservoir and within which a piston 47 is movable, said piston forming an air-tight joint in the cylinder 46 and one of its faces being submitted to the pressure of compressed air; whilst the opposite face is submitted to the action of a 70 75 spring 48.

Said piston 47 is connected by a connecting rod 50 to a wedge 49, mounted so as to slide longitudinally and freely on guiding members 59 carried by the arm 51 of 80 a bellcrank lever, the second arm 52 of which rests on the supervising cam 33, the function of which has been explained in my aforesaid applications.

A connecting rod 54 pivotally connected 85 at one end at 55 to the lever 27 carrying the supervising pointer 25, is provided at its opposite end with a roller 57, constantly in contact with the active face of the wedge 49 and slidable in a groove 58 provided in 90 the arm 57 of the bellcrank lever 51, 52.

This arrangement operates as follows: If the pressure in the brake conduits is normal, the piston 47 will be forced toward the left in the cylinder 46 until the spring 48 balances the air pressure (see Fig. 5).

In this position the wedge 49 will also be forced by the connecting rod 50 to the end of its stroke towards the left, so that the roller 57 will be in contact with the less raised portion of said wedge 49.

Thus said roller will be in its most raised position and the lever 27 will move the pointer 25 to indicate the permissive speed of 120 kilometers per hour.

If the pressure of compressed air decreases, the piston 47 will be moved in its cylinder 46 by the spring 48 until the pressure on both piston faces will be balanced. The connecting rod 50 causes the corresponding movement of the wedge 49, the lower face of which, forming a cam of suitable profile, forces the roller 57 back and causes the same to be lowered, sliding in the groove 58 of lever 51. Thus the connecting rod 54 which carries the roller 57, 110 forces the lever 27 back, the lowering of which causes the supervising pointer 25 to be lowered, said pointer then indicating a limited speed for the train, less than 120 115 kilometers. When the cam 53 (33) is disengaged, as described in my aforesaid applications, the lever 52 which is constantly in contact with said cam, swings and lowers itself according to the profile of said cam 120 and carrying the arm 51 integral with said lever 52 with it towards the cylinder 46.

If the pressure in the brake conduits is normal, said arm 51 will through the agency of the roller 57 and connecting rod or link 130

54 force the lever 57 back, which will thus be progressively moved back to the stop position.

If on the contrary the pressure decreases 5 in the cylinder 46, the wedge 49 moved as above described towards said cylinder, will act on the roller 57 to force the same back and lower the arm 27 and supervising pointer 25. The movement of the wedge 10 49 is of course limited and the stopping thereof is determined by the position given to the piston 47 by the action of the decrease of pressure within the cylinder 46, so that said wedge will not follow the swinging 15 movement of the lever 51, 52 caused by the movement of the cam 33.

After said cam 33 has been moved, the supervising pointer will immediately begin its downward movement; the roller 57 following the incline on said cam and being brought back to its normal position at the end of the movement of said cam.

Therefore the device above described has for its object to modify the lowering of 25 the supervising pointer and permit of the brakes being applied almost immediately after this lowering, whereby the slow action of the brakes will produce the stopping at the point described by the signal, notwithstanding the low pressure.

The second device also serving to act on the supervising pointer to advance or retard the automatic application of the brakes, according as the train runs down 35 or up an incline, is represented in Figure 4.

Said device which is formed by the combination of a pendulum with a mercury-level, comprises two reservoirs 60 and 61, connected to each other at the lower parts 40 by a tube 62 of sufficiently small section to avoid vibrations of the locomotive influencing the level of mercury contained in both reservoirs 60, 61, and into which the lower parts of two floats 63 and 64 are immersed. Said floats are coupled together 45 by a rigid bar 65 parallel to the longitudinal axis of the locomotive and connected at its ends to the rods or stems 66 and 67 of said floats, said bar carrying an arm 50 69, secured at right angles to its central part and inclined from the front to the rear according to the position during the travel of both floats 60 and 61 and so as to remain perpendicular to the level of mercury.

The pendulum 74 is suitably suspended from a point of the locomotive, so as to swing freely around said point and be held in its vertical position. Its swinging movements as well as the movements in opposite direction of the lever 69 are transmitted respectively to the lever 71 which swings around an axis 72 and is connected by a link 73 to a double wedge 79—80, the longitudinal movements of which on the rollers 59

mounted in the head of the lever 51, cause the operation of the roller 57 and actuate the lever 27 carrying the supervising pointer 25.

This device operates as follows:

The parts being in the positions shown in Fig. 4, if the locomotive running in the direction of the arrow X, moves down an incline, the two reservoirs 60, 61 will be inclined according to the incline and the level of mercury will be lowered in 60 and raised 75 in 61 so as to be in the same horizontal plane, whereby the float 63 and 64 will be correspondingly moved and the arm 69 inclined toward the right.

Of course the pendulum 74 will swing 80 towards the left so as to remain in its vertical position and the two movements in opposite directions of the pendulum and the arm 69 transmitted to the lever 71 by the links 70 and 75, cause the lever 71 to swing 85 around the axis 72, said lever being inclined towards the right of the figure.

The end of said lever 71 which is connected to the double wedge 79—80 sliding in the same way and on the same guiding members 59 as the wedge 49 carries said double wedge with it to the right, so that the inclined part of said wedge pushes the roller 57 which moves downwardly and carries the supervising pointer 25 with it through the 95 agency of the link 54 connected to the arm 27 carrying said pointer.

As the train runs up an incline, the pendulum 74 and arm 69 will be inclined in the opposite direction, whereby the lever 71 will 100 push the double wedge 79—80 to the left of the figure.

At a given moment of its stroke to the left, the second part 80 of the double wedge, which is connected to the first part by a spring 82 and guided by the slot 83, is stopped by a stationary lug 81; then the roller 57 is in its uppermost position and the supervising pointer indicates the maximum limit of speed of the train.

This device is completed by a swingable lever 84 which has a notch 85 engaged by a finger 86 on lever 71 and locks the whole during the non-operation of the supervising cam 53.

As said cam is disengaged, a roller 87 carried by the toothed wheel 88 causing the rotation of said cam 33, engages lever 84, causes the same to swing and thus disengages the lever 71 which displaces the wedge 79 120 and brings the same to a position determined by the inclination of the track as above described.

As the wedge is held in this position during the swinging movements of the levers 125 51—52, the incline slides on the roller 57 so that the braking action will begin sooner. Thus this device permits of the action of the supervising cam being modified according to the inclination of the track, whereby the 130

stopping of the train may be secured within the regulating distance of 1000 meters.

A braking member formed of a drum 89 with longitudinal corrugations receives a 5 rotary movement from the shaft 90 of the usual governor, said movement being transmitted by pinions 91 and 92.

Said drum at regular intervals and by the 10 action of a spring 93 will frictionally engage the lower face of the mass of the pendulum, so as to limit the swinging movements thereof and avoid amplifications of said movements by shocks of the locomotive.

From the foregoing it will be seen that 15 the combination with the controlling apparatus forming the subject matter of my aforesaid applications, of the devices above described permits of an apparatus of absolute safety being realized.

20 In fact, the speed of a train being limited automatically according to the pressure of compressed air in the main conduit, the engineer cannot go beyond the speed allowed by said pressure and he may in running at 25 a reduced speed stop the train within the regulating distance of 1000 meters.

With the device retarding or advancing the moment of automatic braking of a train running up or down an incline, the engineer 30 is enabled, in running up an incline, to run at full speed, the 1000 regulating meters being more than sufficient to permit of the train being stopped, if during the upward running he meets with a signal at "Stop," 35 the device retarding the contact of the supervising and speed pointers enabling the engineer to apply the brake a little later.

On the contrary if the train runs down an 40 incline, the speed of the train must be reduced at the very beginning of the incline. As the device advances the contact of the supervising and speed pointers, the limit of speed will be decreased and therefore the speed of the train will be reduced automatically. If the train meets with a signal at 45 "Stop" in the course of its downward movement, the braking action will be much more forceful since the contact of the two pointers is almost immediate and the train may stop 50 within the normal distance of 1000 meters.

Having now fully described my said invention, what I claim and desire to secure by Letters Patent, is:

1. A speed controlling apparatus for railway trains, comprising in combination a speed controlling cam, a stop lever for maintaining said cam in its locked position and means for effecting the disengagement of the said stop lever by a lug on the track, 55 said means comprising a compressor formed of a cylinder mounted horizontally below the locomotive, an air pocket on the apparatus, a duct connecting said cylinder with said air pocket, a spring actuated piston 60 within said cylinder, and a flexible member

attached to the piston and stretched below the locomotive for being engaged by said lug on the track at the passage of the train, whereby compressed air may be forced into said pocket. 70

2. A speed controlling apparatus for railway trains comprising in combination a speed controlling cam, a stop lever for normally maintaining said cam in its locked position, means for rotating said stop lever 75 out of engagement with said cam, said means comprising a resilient air pocket which, when becoming inflated, rotates said lever, a compressor cylinder for injecting air into said pocket, a spring actuated piston within 80 said cylinder, a transverse chain at the lower part of the locomotive and connected at one of its ends to the rod of said spring actuated piston, with the opposite end connected to a spring actuated rod slidably 85 disposed within a hollow boss, a plug closing said boss, a contact finger and a valve stem engaged within said plug, an electric circuit, an electromagnet inserted in said circuit below the stop lever, a valve at the 90 end of the valve stem and closing normally a conduit branched on the main air conduit of the brakes and opening into a resilient air pocket below the stop lever, said second 95 air pocket operating the stop lever in the same manner as the first named air pocket, whereby in case of rupture of the said chain, the said spring actuated rod will be moved backwardly, thus producing the closure of the electric circuit and the opening of the 100 communication between the main conduit of the brakes and the second air pocket and consequently the rotary motion of the stop lever for releasing the speed controlling cam. 105

3. A speed controlling apparatus for railway trains, comprising a plurality of speed controlling cams, having different profiles, a speed controlling pointer, a controller lever for operating said speed controlling 110 pointer and means operated by the driver for bringing said controlling lever in front of one of said cams, according to the speed to be permitted for the train.

4. In a speed controlling apparatus for 115 railway trains, a device for limiting the speed of the train in accordance with the degree of pressure of the compressed air in the main conduit, comprising a supervising cam, a cylinder in connection with the 120 main conduit of the brake device, a spring operated piston tightly slidable within said cylinder, a wedge shaped block, a connecting rod connecting the piston with said block, members for guiding said block and 125 carried by one arm of a bell crank lever, the second arm of which rests on the supervising cam, a connecting rod connected at one end with said second arm, and a roller secured at the opposite end of said 130

connecting rod and constantly in contact with the cam shaped face of said wedge, said roller sliding in a groove of said bell crank lever, whereby, according to the pressure of the compressed air in the conduit, the said spring actuated piston assumes different positions within the cylinder, which causes the supervising pointer to rotate and be moved back from the position corresponding to highest speed down to the stop position.

5. In a speed controlling apparatus for railway trains, a device for operating a supervising pointer in view of advancing 15 or retarding the automatic application of the brakes, according as the train runs down or up an incline, said device comprising in combination a pendulum with mercury level composed of two reservoirs, a 20 duct of small diameter connecting both reservoirs, a float in each of said reservoirs,

a rigid bar connecting both floats, an arm extending from said bar at right angles to its central part and inclining from the front to the rear according to the position during 25 the travel, of both floats, a pendulum suspended on the locomotive, hinged connections between said pendulum and the arm on the said rigid bar, a double wedge, connecting links between said wedge and the 30 pendulum on one hand, and between said wedge and the said bar on the other hand, and links having rollers mounted on the said wedge for causing the operating of the 35 supervising pointer.

In testimony whereof I have hereunto set my hand in presence of two witnesses.

ELOI RODOLAUSSE.

Witnesses:

FRANÇOIS LENAERT,
ARTHUR CHOKUR.
